UNITED STATES PATENT OFFICE.

ENRICO GALLO, OF PITTSSTON, PENNSYLVANIA.

SCRUBBING AND MOPPING MACHINE.

1,150,025.

Specification of Letters Patent. Patented Aug. 17, 1915.

Application filed November 10, 1914. Serial No. 871,377.

To all whom it may concern:
Be it known that I, ENRICO GALLO, a citizen of the United States of America, residing at Pittston, in the county of Luzerne 5 and State of Pennsylvania, have invented certain new and useful Improvements in Scrubbing and Mopping Machines, of which the following is a specification, reference being had therein to the accompanying drawing.
10

This invention relates to floor scrubbing machines and has for its principal object the production of a simple and efficient device which will efficiently scrub the floor as the 15 brushes are being soaped.

Another object of this invention is the production of a floor scrubbing machine wherein a plurality of housings are employed for the carrying of soap bars in such 20 a manner as to be readily engaged by the horizontally rotating brushes so that as the brushes are supplied with water they will be soaped for cleansing the floor.

With these and other objects in view this 25 invention consists of certain novel combinations, constructions, and arrangements of parts as will be hereinafter fully described and claimed.

In the accompanying drawing: Figure 1 30 is a central longitudinal section of the scrubbing machine, as constructed in accordance with this invention; Fig. 2 is an enlarged longitudinal section of the forward portion of the scrubbing machine showing the manner in which the soap is fed to the brushes. Fig. 3 is a section taken on the line 3—3 of 35 Fig. 2.

By referring to the drawing it will be seen that 1 designates the outer casing which is 40 supported upon a plurality of forward wheels 2 and a plurality of rearward wheels 3. The casing 1 carries near the front thereof a pair of brushes 4, which brushes are supported upon the casing 1 under the platform 5. The platform 5 carries a plurality 45 of soap containing housings 6 in which are placed soap bars or cakes 7. A pressure plate 8 is carried upon each soap bar or block 7 and each plate 8 carries a spring 9 for urging a downward pressure upon the soap bars 7 and thereby normally holding 50 the soap bars in firm engagement with the brushes 4.

As clearly illustrated in Fig. 2, two of 55 these brushes are employed, each brush cooperating with a soap bar for facilitating

the soaping of the brush to assist in scrubbing the floor over which the machine is adapted to travel.

One of the brushes 4 is driven by means of 60 a sprocket chain 10, while a sprocket chain 11 is placed upon the opposite side of the casing 1, as shown in Fig. 3, and these chains 10 and 11 are adapted to be driven by any suitable sprocket, not deemed necessary to 65 be herein disclosed, carried by the forward wheels 2, which are mounted upon the axle 14.

A water supply tank 15 is supported within the main casing 1, and this water supply 70 tank 15 tapers toward the bottom and top thereof to constitute a substantially diamond shaped structure in cross-section. The tank or reservoir 15 is provided with a bottom partition 16 through which extends the 75 valve 17 for normally closing the aperture 18 formed in the partition 16. The valve 17 is carried by a vertically extending plunger 19 upon which plunger is carried a coil spring 20 for normally urging a downward 80 pressure upon the valve 17. The upper end of the spring 20 engages the inner end of the tank 15 as clearly illustrated in Fig. 1. It should be understood that a suitable door 21 may be employed for the purpose of filling 85 the tank 15. As clearly illustrated in Fig. 1, the partition 16 is spaced from the lower end of the tank 15.

A water discharge pipe 22 communicates 90 with the tank 15 below the partition 16, and this water discharge pipe is provided with a plurality of apertures 23 near the lower end thereof. The pipe 22 is also provided with laterally extending sections 24 which are also 95 perforated as indicated at 25 for evenly distributing water throughout the entire length of the brushes 4. The water, of course, will be discharged upon the floor which is being scrubbed, and by rotating the brushes 4 it will be seen that a floor may be scrubbed 100 easily and readily cleaned by moving the casing 1 back and forth according to the desire of the operator.

From the foregoing description it will be 105 seen that a very simple and efficient floor scrubbing machine has been provided, wherein the soap housings will efficiently carry the soap bars by means of the lower portions, as clearly shown in Fig. 2, while the lower portions of the housings are open 110 so as to allow said bars to be easily engaged by the rotary brushes, so that as the water

is sprayed by the brushes and the brushes rotated, they will engage the soap and by continuous action will scrub the floor.

Having thus described the invention what is claimed as new, is:—

1. In a floor-scrubbing machine, the combination of a casing, a platform carried within said casing, soap-containing housings carried by said platform, cylindrical horizontally extending scrubbing brushes carried by said casing directly beneath said soap containing housings, means for rotating said brushes, said housings being adapted to contain bars of soap, said housings having unobstructed open lower portions, whereby said brushes may engage the soap bars for soaping the surface being scrubbed as the brushes are rotated.

2. In a floor-scrubbing machine, the combination of a casing having cylindrical horizontally extending rotatable brushes carried directly beneath said soap containing housings, means for rotating said brushes,

a platform carried within said casing above said brushes, soap-containing housings carried beneath said platform, inwardly extending flanges formed upon the lower portions of said housings, the lower portions of said housings being open and unobstructed, said brushes being adapted to extend into said housings between said flanges, said housings being adapted to contain bars of soap, means carried within said housings for bearing upon the soap bars for exerting a downward pressure thereon, whereby the soap bars will be held in engagement with said brushes so as to cause said brushes to soap and scrub a floor as they rotate, said flanges being adapted to limit the downward movement of the soap bars.

In testimony whereof I hereunto affix my signature in presence of two witnesses.

ENRICO GALLO.
